UNITED STATES PATENT OFFICE.

GEORGE S. STRONG, OF PHILADELPHIA, PENNSYLVANIA.

VALVE-MOTION.

SPECIFICATION forming part of Letters Patent No. 320,895, dated June 23, 1885.

Application filed April 3, 1885. (No model.)

To all whom it may concern:

Be it known that I, GEORGE S. STRONG, a citizen of the United States, residing in Philadelphia, Pennsylvania, have invented certain 5 Improvements in Valve-Motions for Steam-Engines, of which the following is a specification.

My invention consists of mechanism described hereinafter, by which the valve of a 10 steam-engine may be operated from the crank shaft or axle and connecting-rod, the movement obtained being essentially the same as that obtained by the devices which form the subjects of my Patents Nos. 304,970 and 304,972, 15 of September 9, 1884, and No. 315,972, of April 14, 1885.

In the accompanying drawings, Figure 1 is a side view of my improved valve-gear applied to a locomotive-engine; Fig. 2, a plan view; Fig. 3, a perspective view of the valve-gear; Fig. 4, a general diagram illustrating the action of my improved valve-gear; Figs. 5 and 6, diagrams illustrating the action of parts of the valve-gear; Fig. 7, a view of my 20 improved valve-gear in its simplest form, and Fig. 8 a modified form of the gear.

Referring in the first instance to Figs. 1, 2, and 3, W is the cylinder of a locomotive-engine, and V V the valve-lifter chests, v being the 30 rock-shafts for the lifters, which are attached to the valve-rods B B'. In the present instance the valves are what are termed "grid-iron-valves," as shown in the diagram, Fig. 4.

A is the connecting-rod of the engine, secured to the usual cross-head, guided in ways w, projecting from the cylinder W. B is the steam-valve rod, and B' the exhaust-valve rod. 35

To simplify the explanation of the parts, I will describe the steam-valve-operating mechanism, as it is duplicated in the exhaust-valve mechanism, as shown hereinafter.

D is a fixed segment made in the arc of a circle, and secured to any available fixed part of the engine, the dotted line x representing 45 the central line of the engine—that is, a line passing through the center of the cylinder and that of the crank-shaft. It is also the central line of the connecting-rod when the crank is either at its rear or front dead-center.

50 In Fig. 1 the crank-pin is supposed to be at the rear dead-center.

To the segment D is fitted a block, E, which

is adjusted thereon. One end of a link, F, is secured to this block E by a pin, e, the opposite end of the link being connected by a pin, 55 f, to a lever, H, which has a short arm, h, connected by a pin, d, to one end of a rod, G, the opposite end of the latter being connected by a pin, b, to the valve-rod B, which is also connected to the upper end of a rocking link, I, 60 by a pin, i, the lower end of the latter being hinged by a pin, g, to any available fixed part of the engine. This rocking link supports the end of the valve-rod B and link G when the two are connected together. 65

All the above-described features are shown and specified in my Patent No. 304,970, of September 9, 1884, and it is the combination of these features with the following which I wish to secure by Letters Patent. A lever, 70 J, is attached to the connecting-rod A by a pin, m, the other end of the lever being attached to a link, K, by a pin, k. This link K is pivoted to a fixed part of the engine on the same side of the connecting-rod as the rest 75 of the valve-gear. The rod H is connected to the lever J by a pin, l, in the present instance about midway between the pins m and k. The object of the lever J and link K, constructed and combined as described, is to 80 overcome the error that would ensue if the lever H were pivoted directly to the connecting-rod A, as it is necessary to have an equal opening of the ports at both ends of the cylinder; hence by pivoting the lever J to the 85 connecting-rod A at m, and the rod H to the lever at l, the pin l will describe the irregular oval P, which extends about double the distance below the line x as it does above, thus compensating for the error. 90

I have described above only the steam-valve-operating mechanism; but the same description will apply to the exhaust-valve-operating mechanism, as it is identical both in construction and operation, and I have lettered the parts of the exhaust apparatus "prime." Both mechanisms can be operated independently of each other by means of the rods j j', which connect the blocks E E' with the operating-stand in the cab of the engine. 95

In explaining the operation of the above-described valve-motion, reference may be had to Figs. 1 and 4, the line x in the diagram, Fig. 4, corresponding with the line x in Fig. 1. 100

The parts as illustrated in Fig. 1 are in the position shown when the crank-pin *a* is at its rear dead-center—that is, the pin *a* is at its nearest point to the cylinder, the piston being 5 at the rear end of the same, the center line of the rods shown by full line and marked with the same reference-letters as Fig. 1.

The circle *M* indicates the path of the center of the crank-pin *a*, the oval *N* the path of the 10 pin *m*, the irregular oval *P* the path of the pin *l*. The block *E* is midway between the two extreme adjusting-points—that is to say, “mid-gear.”

When the crank-pin *a* has been moved in 15 the direction of its arrow in the diagram until it is at the outward dead-center—that is, at number 24—the several pins *m*, *l*, and *k* will also be at the points numbered 24 in their several paths. The pin *f* will be in the same position when the crank-pin is at its front dead-center, 24, as when at its rear dead-center, 1; but the pin *d* will have a movement from 1 in the direction of its arrow to 24, as shown 20 in the enlarged diagram, Fig. 5, being one-half of an irregular oval, the pin *f* moving to the point number 12 and back again to 24, when the block *E* is at mid-gear. (See Fig. 6.)

When the crank-pin *a* is at 24, the piston of the engine will be at its extreme forward limit. 30 In returning, the crank-pin *a* travels from the front dead-center to the rear dead-center, 48 or 1, in the direction of its arrow, the pins *m* and *l* traveling the upper half of the path to 48 or 1; but the pin *k* travels in 35 the same path going from the front to the rear dead-center as in going from the rear to the front dead-center. The pin *f* travels from the point 24 to the extreme point 36, Fig. 6, back again to 48 or 1, the pin *b* traveling from 40 24 to 48, being the remaining half of the irregular oval, as described above, and indicated by the dark section, Fig. 5. It will now be seen that a compound movement is imparted to the lever *H*—namely, first, a vibrating 45 movement on its fulcrum-pin *f*, and, second, a movement of the lever by which, under the control of the rod *F*, the fulcrum-pin is caused to traverse in the arc of the circle. To this second movement is due the throw of the valve, 50 the extent and direction of the throw being determined by the adjustment of the block on the segment. To the first movement—that is, to the vibration of the lever on its fulcrum-pin—is due the lap-lead and cut-off of the 55 valve.

I have shown both in Fig. 1 and the diagram, Fig. 4, the block *E* in its mid-gear position, (marked *z*.) The movement of the crank-pin when the block *E* is in this position will 60 not affect the fulcrum-pin *f*, and consequently will not open the valve-ports; but the lever *H* will have its vibrating movement on the fulcrum-pin, and the pin *d* will describe the irregular oval *u*, (shown by dark section, Fig. 5,) 65 which will not affect the opening of the valves. By moving the block *E* from the mid-gear position *z* to the full-throw position *z'*, the pin *f*

will travel in the arc of the circle *w'*, Fig. 6, and the pin *d* will travel in the irregular path *u'*, Fig. 5, the ports of the engine being full 70 open, and having the required lap-lead and cut-off. Should the block *E* be adjusted to the position *z''*, the travel of the fulcrum-pin will be in the arc of the circle *w''*, and the motion of the valve reversed. The pin *d* will 75 travel in the irregular path *u''*, Fig. 5.

Turning now to Fig. 8, which represents the valve-motion without the lap-lead and cut-off gear, the block *E* being raised on the segment *D*, in this instance the arm *h* of the 80 lever *H* is dispensed with, and the rod *G* connected directly to the pin *f*. This gear is intended to be used on engines in which the lead of the valve is obtained by mechanism outside of the valve-operating mechanism. When the 85 block *E* is at mid-gear *z*, there will be no movement whatever of the valve-rod, the pin *f* traversing in the arc *w*; but when the block has been adjusted to its lowest point, *z'*, the pin *f* will traverse in the arc *w'* and the valve will have 90 its full throw. Should the block be adjusted to the position *z''* the pin *f* will traverse in the arc *w''*, and the motion of the valve will be reversed.

Referring to Fig. 7, which represents the 95 valve-motion in its simplest form, the rod *F* is secured to a position on any fixed part of the engine, the valve-rod *B* in this instance sliding in a bearing in this fixed projection. In this case the engine is intended to run forward, and is regulated by the ordinary throttle-valve. In most cases it is desirable to make the valve-motion, as shown in Fig. 1, and as illustrated in the diagram, Fig. 4, so that the two movements of the valve may be obtained, 100 one being the ordinary throw of the valve, the other the lap-lead and cut-off of the valve.

It will be observed that owing to the combination, with the devices of my former patents, of the lever *J*, and of the pivoted link *K* on the same side of the connecting-rod as the other levers, none of the valve-gear lies below the connecting-rod—a feature of importance, especially in locomotives, for in the latter it is desirable to have the operating-levers as far 110 from the track as practicable, so as to avoid the throwing of dirt up into the working parts, and also to avoid possible obstructions along the track striking such levers as might lie below the connecting-rods.

In other forms of engines the construction described takes all the valve-gear away from the bed-plate or condenser and makes the structure more compact.

I have shown in the diagram, Fig. 4, my 125 valve-motion as applied to a gridiron-valve; but it will be understood that the motion can be applied to different forms of valves as well.

I claim as my invention—

1. The combination, in valve-gear for steam-engines, of the following elements, namely: first, the pivoted link *F*, having a fulcrum-pin, *f*; second, a connecting-rod, *A*, lever *J*, pivoted thereto and to a pivoted link, *K*, on the 130

same side of the connecting-rod as the rest of the valve-gear, a rod, H, pivoted to the lever J and to the link F by the fulcrum-pin f; third, a link, G, connected also to the fulcrum-pin f and to the valve-rod B, all substantially as set forth.

2. The combination, in valve-gear for steam-engines, of the following elements, namely: first, a fixed segment, D, and a block, E, adjustable thereon; second, a lever or link, H, and connecting-rod A, lever J, and link K, pivoted on the same side of the connecting-rod as the rest of the valve-gear, for imparting the within-described compound movement to

15 the lever H; and, third, a link, F, connecting the adjustable block to the lever H by a pin, f, to which lever is also connected the valve-rod, substantially as set forth.

3. The combination, in valve-gear for steam-

engines, of the following elements, namely: 20 first, a fixed segment, D, and a block, E, adjustable thereon; second, a lever, H, having its fulcrum-pin connected to the said block, and having an arm, h, connected to the valve-spindle; and, third, the connecting-rod A, lever 25 J, and link K, pivoted on the same side of the connecting-rod as the rest of the valve-gear, for imparting the within-described movement to the lever H, all substantially as set forth.

In testimony whereof I have signed my name to this specification in the presence of two subscribing witnesses.

GEORGE S. STRONG.
